(57) **CLAIM**

The ornamental design for a corner support of a casket lowering device, substantially as shown and described.

DESCRIPTION

FIG. 1 is a perspective view of the corner support design of the present invention, showing a corner of a casket vault in phantom;

FIG. 2 is an enlarged perspective view of the corner support design of the present invention;

FIG. 3 is a top view of the corner support design of the present invention;

FIG. 4 is a bottom view of the corner support design of the present invention;

FIG. 5 is a rear view of the corner support design of the present invention;

FIG. 6 is a front view of the corner support design of the present invention;

FIG. 7 is a right side view of the corner support design of the present invention; and,

FIG. 8 is a left side view of the corner support design of the present invention.

The broken line showing of the casket in FIG. 1 is for illustrative purposes only and forms no part of the claimed design.
